UNITED STATES PATENT OFFICE.

ERNEST H. FOSTER, OF NEW YORK, N. Y.

LOCOMOTIVE-SUPERHEATER.

1,151,934.

Specification of Letters Patent. Patented Aug. 31, 1915.

Application filed November 3, 1913. Serial No. 798,818.

To all whom it may concern:

Be it known that I, ERNEST H. FOSTER, a citizen of the United States, residing at New York, county of Richmond, and State of New York, have invented certain new and useful Improvements in Locomotive-Superheaters, of which the following is a full, clear, and exact description.

The invention which constitutes the subject-matter of this application relates to improvements in steam superheaters, and while the present embodiment has been particularly designed for locomotive superheating, it is to be understood that the invention is not confined to this specific use.

The invention has to do with that type of superheater in which the individual superheating elements are projected rearwardly from the smokebox into the fire tubes of the locomotive boiler, and the invention pertains largely to the construction of these headers and superheating elements and the relation of the headers and superheating elements to each other and to the smoke box of the locomotive.

In the drawings, Figure 1 is a longitudinal section of my invention, showing the relation of the superheater to the locomotive boiler and smoke box, so much only of the boiler and smoke box being exhibited as will illustrate the use and the application of the invention. Fig. 2 is a view taken substantially on the line 2—2 of Fig. 1.

Referring to the drawings in detail, the reference character 10 designates a conventional type of locomotive provided with a smoke box 11. Located in the smoke box and attached to the tube sheet 12 is a cylindrical or drum header 13 provided with a saturated steam compartment 14 adapted to receive steam through the pipe 15 from the steam dome (not shown) of the boiler and a superheated steam compartment 16 adapted to receive superheated steam from the superheating tubes. Pipes 17 are connected at one of their ends to the head 18 of the superheated steam compartment and the other end of these pipes are connected to the steam chests of the locomotive. The saturated steam compartment 14 and superheated steam compartment 16 are separated by means of a suitable partition 19.

The superheater coils 20 are arranged in different lengths, one end 21 of each being expanded into the saturated steam compartment 14 and the other end 22 of each being

expanded into the said superheated steam compartment 16. The coils proper project into the forward end of a plurality of series or sets of fire tubes 23, as clearly illustrated, and it will be evident that saturated steam coming into the saturated steam compartment 14, through the dry pipe 15, will pass through the superheater coils 20 into the superheated steam compartment 16 and thence to the steam chests through pipes 17.

From the foregoing description it will be seen that the form and arrangement of superheater which I have described can readily be installed in the various makes of boilers. It is straight-forward boiler work, both in construction and fastening to the boiler, presents a minimum amount of calking edges and avoids the necessity of fitting plates to the boiler which is not only expensive work, but work of a very difficult and tedious nature, especially when done in the field. The header, as stated before, is of substantially cylindrical or drum form and its axis is preferably arranged parallel to the axis of the fire tubes. This arrangement readily lends itself to receive steam through one end thereof from the usual dry pipe 15 and to discharge steam from the other end through the discharge pipes 17. By virtue of this arrangement, too, the connection between the header and dry pipe 15 on the one hand and the connection between the header and the discharge pipes 17 on the other are readily accessible, making the assembling and disassembling operations of the simplest form, and reduces the riveting and calking to a minimum.

Another important advantage of this superheater is the fact that the cylindrical form of the header saves more space, as compared with any other form heretofore proposed, thereby giving greater accessibility to the other parts of the locomotive and allows more room for making repairs. At the same time its form, as will be apparent, is such as to require the least amount of material to give the required area for the passage of the steam and for the necessary tube and pipe connections. The cylindrical header is preferably made of a tube flanged at both ends, or may be made of a plate bent to the form of a tube with the ends either welded or riveted. The ends 21 of the superheating coils are connected to the saturated steam compartment of the header, preferably in a plurality of substantially

- circumferential rows, each row corresponding to a horizontal row or series of fire tubes. It will be noted, however, that the individual fire tubes are located below and at different distances from the circumference of the cylindrical header. I therefore provide a novel arrangement which not only makes all necessary provision for expansion of the superheating tubes, but also makes provision for spacing the ends of these tubes uniformly throughout the front of the smoke box. To do this I extend the ends of each of these tubes from the header radially outward to a point approximately above the fire-tube in which that particular superheating coil is placed, taking care of course not to make a sharp turn at the point or points referred to. From these points the ends of the superheater tubes are dropped substantially vertically downward to points in alignment with the particular fire tube opening, as clearly shown in Fig. 1. The rows of superheater tubes circumferentially connected to the lower curved side of the header may be arranged in any desired longitudinal relation with respect to each other.
- In order to provide access to the dry pipe 15 for repair or for replacement, the header, in addition to being provided with a removable head 18, has also a removable closure 27 in the partition 19. By removing the head and the closure together with the semi-circular rings 24, the pipe 15 may be withdrawn through the header. The ends of all the superheater tubes are accessible through the hand holes 25 in the header, and the arrangement is such that any set of tubes may be readily removed for replacement or repair. In order to make the tubes accessible while the header is in position, I may provide, in addition, the hand holes 26 in the wall of the smoke-box. For the purpose of regulating the flow of furnace gases through those fire tubes which contain the superheater coils, I employ a baffle 28 and a damper 29, the arrangement being such that when the latter is in closed position the passage of gases through the sets of tubes 28 is prevented. The header is supported at its front end by means of the tube sheet, and aside from this, it has no other connection either to the boiler or to the smoke box. As a result, the whole arrangement has practically absolute freedom of expansion.
- From the foregoing it will be obvious that I have devised a superheater of simplest construction; requires a minimum amount of material for a maximum amount of superheating area per quantity of material used; all the parts have provision for free expansion; the arrangement permits free and unrestricted circulation; provides more space thereby giving greater accessibility for repairs; and a superheater capable of being installed on the various types of boil-

ers now in use, particularly locomotive boilers.

It is to be understood that I do not confine myself to the exact construction shown, as many changes may be made in point of detail and other embodiments resorted to without necessarily departing from the true spirit and scope of my invention.

What I claim is:—

1. A boiler provided with fire tubes, in combination with a superheater comprising a cylindrical or drum header having a saturated steam compartment and a superheated steam compartment, means for connecting the saturated steam compartment with the steam dome of the boiler, means for connecting the superheated steam compartment with the steam chest, and superheating elements connected to said header, the coils of which are in the fire tubes and the inlet ends of which are expanded into said saturated steam compartment and the other ends of which are expanded into the superheated steam compartment.

2. A boiler provided with fire tubes, in combination with a superheater comprising a cylindrical or drum header having saturated and superheated steam compartments, and a plurality of superheater tubes expanded into said compartments and projecting from said drum in substantially radial paths, the coils of said tubes projecting into said fire tubes of the boiler.

3. A boiler provided with fire tubes and a tube sheet, in combination with a superheater comprising a cylindrical or drum header having a partition therein dividing the same into saturated and superheated steam compartments, and a plurality of superheater tubes expanded into said compartments and projecting from said drums substantially in radial paths, said header supported at one end by the tube sheet of the boiler, and the coils of the superheater tubes projecting into the fire-tubes of the boiler.

4. A boiler provided with fire tubes, in combination with a superheater comprising a cylindrical or drum header having a partition therein dividing the same into saturated and superheated steam compartments, and a plurality of sets of superheater tubes expanded into said compartments, said sets of tubes located in substantially circumferential rows on the lower curved side of the header and projecting from said drum substantially in radial paths, the coils of said superheater tubes projecting into the fire-tubes of the boiler.

5. A boiler provided with fire tubes, in combination with a superheater comprising a cylindrical or drum header divided into saturated and superheated steam compartments and the axis of which is parallel to the axes of said tubes, superheater

- 5 tubes expanded into the curved side of said header with one of the ends of each of said tubes leading into the saturated steam compartment and the other end of each of said tubes leading into said superheated steam compartment, an inlet for the saturated steam compartment, and an outlet for the superheated steam compartment.
- 10 6. A boiler provided with fire tubes, in combination with a superheater comprising a cylindrical or drum header divided into saturated and superheated steam compartments and the axis of which is parallel to the axes of said tubes, superheater tubes provided with coils projecting into said fire tubes, one of the ends of each of said tubes connected to said saturated steam compartment and the other end of each of said tubes connected to said superheated steam compartment, the said ends of the said superheating tubes projecting outwardly in a radial path from said drum and arranged circumferentially around the latter.
- 15 7. A boiler of the locomotive type provided with a smoke box, and a tube sheet, in combination with a superheater comprising a cylindrical or drum header arranged in front of the tube sheet and parallel to the boiler and provided with saturated and superheated steam compartments and openings at either end thereof to said compartments, a dry pipe projecting through the tube sheet and secured in the opening at one end; a partition between said compartments provided with an opening, and removable closures for the opening in said partition and for the opening in the other end, the last mentioned opening and the opening in said partition being large enough to permit access to said dry pipe for repair and replacement.
- 20 8. A boiler of the locomotive type provided with fire tubes, in combination with a superheater comprising a cylindrical or drum header provided with a steam inlet at one end of said cylinder opening into a saturated steam compartment and a steam outlet opening at the other end of said cylinder opening into a superheated steam compartment, and superheating elements, one of the ends of each of which is expanded into said saturated steam compartment and the other end of each of which is expanded into said superheated steam compartment.
- 25 9. A boiler provided with fire tubes, in combination with a superheater comprising a cylindrical or drum header with its axis in substantial parallelism with the axes of the fire tubes and provided with a saturated and a superheated steam compartment, and superheater tubes lying in the fire tubes and each having its ends lying one in front of the other and expanded into said saturated and superheated steam compartments, the said tubes projecting from said drum in substantially radial paths at their extreme ends and then curving downwardly and extending to the fire tubes and arranged so that no tube lies in front of another whereby any tube may be removed without necessarily disturbing the other tubes.
- 30 10. The combination with a boiler having fire tubes and a smoke box, a drum having its upper wall imperforate and its lower wall perforated to receive the ends of superheater tubes, and having a relatively large opening in its front wall, a partition dividing the drum into two headers, a plurality of superheater tubes lying in the fire tubes with their ends expanded into the wall of the drum on opposite sides of the said partition, and a removable outlet T secured over said relatively large opening in the front wall of the drum, whereby access is given to the ends of the tubes when the T is removed.
- 35 11. The combination with a boiler having fire tubes and a smoke box, a drum having its upper wall imperforate and its lower wall perforated to receive the ends of superheater tubes, and having a relatively large opening in its front wall, a partition dividing the drum into two headers with an opening therethrough opposite said relatively large opening, a removable closure for said opening in the partition, a plurality of superheater tubes lying in the fire tubes with their ends expanded into the wall of the drum on opposite sides of the said partition, and a removable outlet T secured over said relatively large opening in the front wall of the drum, whereby access is given to the ends of the tubes when the T is removed.

In testimony whereof I affix my signature in the presence of two subscribing witnesses.
